COMBINATION PICTURE FRAME AND ALBUM

Bernard J. Zenner and Ingrid Zenner,
New York, N. Y.

Application April 30, 1949, Serial No. 2,356

Term of patent 3½ years

(Cl. D61—1)

To all whom it may concern:

Be it known that we, Bernard J. Zenner, a citizen of France, and Ingrid Zenner, a citizen of the United States, both residing in the city of New York, in the county of New York and State of New York, have invented a new, original, and ornamental Design for a Combination Picture Frame and Album, of which the following is a specification, reference being had to the accompanying drawings, forming part thereof.

In the drawings, Figure 1 is a front elevational view of a combination picture frame and album, showing our new design.

Figure 2 is a rear elevational view.

Figure 3 is a perspective view showing the combination picture frame and album in the open position for displaying pictures in the album.

Figure 4 is a side elevational view.

The essential features of our design reside in the parts shown in full lines.

We claim:

The ornamental design for a combination picture frame and album, as shown and described.

BERNARD J. ZENNER.
INGRID ZENNER.
